UNITED STATES PATENT OFFICE.

FREDERICK W. PENNOCK, OF QUEBEC, QUEBEC, CANADA.

LAMP GUARD AND SHADE.

1,244,640.

Specification of Letters Patent.

Patented Oct. 30, 1917.

Application filed January 26, 1917. Serial No. 144,782.

To all whom it may concern:

Be it known that I, FREDERICK W. PENNOCK, a subject of the King of Great Britain, residing at Quebec, in the Province of Quebec and Dominion of Canada, have invented new and useful Improvements in Lamp Guards and Shades, of which the following is a specification.

This invention relates to combined lamp guards and shades and particularly to that type of the same which is capable of being locked upon the socket of an electric bulb.

The principal object of the invention is to provide a combined lamp guard and shade, which may be locked to an incandescent bulb for the purpose of preventing breakage of the same, and to prevent the removal of the bulb, guard and shade by unauthorized persons.

20 A further object of the invention is the provision of a device of this class which is capable of being readily secured to the lamp socket and will act as a protector, for the lamp and a shade for the eye.

25 A still further object of the invention is the provision of a device of this class which is neat and attractive in appearance, of simple construction and one that may be manufactured and sold at a nominal cost.

30 With the above and other objects in view the invention consists of a lamp guard preferably formed of wire and provided with a split collar by means of which it is locked to the lamp socket of an incandescent bulb 35 and the sectional pivoted shade secured to the split sections of the said collar.

In the drawings;

Figure 1 is an elevation of the invention illustrated in its open position and about to be applied to an electric light bulb, the lamp guard being shown in dotted lines;

Fig. 2 is a top plan view of the invention in its closed position removed from the lamp socket; and

45 Fig. 3 is an enlarged detailed vertical sectional view of the combined guard and shade applied to the lamp socket, the said socket being shown in elevation.

In factories or other places employing 50 large numbers of men and where artificial light is required it has been found that great loss has been suffered by the breakage and removal of incandescent lamps. It is necessary for the comfort of the employees to 55 provide these lamps with shades and as the lamp socket will not permit of the use of

a shade and a lamp guard upon the same socket, the guard is omitted, resulting in a large percentage of breakage and removal of the lamp bulbs. In order to prevent the 60 breakage and removal of these bulbs and at the same time protect the eyes of the worker there has been devised the following described combined lamp guard and shade which is capable of being securely locked 65 in position upon the socket of the lamp.

Referring in detail to the drawings the numeral 10 designates a lamp guard of the wire cage type, the said guard being formed in sections 11 and 12, which are hinged together having their free ends pivotally mounted within the disk 13 in the usual way. The upper or opposite ends of these sections are secured to a split collar 14, by having the said ends passed through apertures and bent over as shown. The collar 14 is composed of the sections 15 and 16, and are provided with laterally extending flanges 17 and 18 for the purpose of providing means for locking the collar together. 70 This lock is designated at 19 and made of any preferred construction, the one shown being provided with a projection 20 which passes through apertures in the flange 17 for the purpose of receiving a suitable key by 75 means of which the sections of the collar are locked together. Each of the sections 15 and 16 are formed with flanges 21, which when the sections are secured together form an annular flange provided with a depending flange 22, which provides means for securing the cage of the lamp guard to the 80 collar as before described.

Secured to the collar 14 is a lamp guard 23, the said guard being composed of sections 24 and 25 which are pivoted together as shown at 16. The upper ends of the sections 24 and 25 are provided with inturned flanges 28 which when together form an annular inturned flange which is adapted to 100 overlie the annular flange 21 of the collar and be secured thereto by means of rivets or any other suitable fastening means. As will be seen from Fig. 1 of the drawings the sections 15 and 16 of the collar are secured 105 to the sections 24 and 25 respectively of the lamp guard and as the said guard and collar are pivoted both at their lower ends provide a combined pivoted lamp guard and shade which is capable of being conveniently and 110 quickly secured and locked in position upon the socket of an incandescent lamp.

Having described the invention, what is claimed is;

1. A combined lamp guard and shade comprising a guard provided with a split collar, a sectional shade secured to said collar and means for locking the split portions of said collar together.
2. A combination lamp guard and shade comprising a guard provided with a split collar, a sectional shade secured to said collar, said sections being hinged together and means for locking said collar upon a lamp socket.
3. A combined lamp guard and shade comprising a guard provided with a split

collar, an annular offset portion formed on said collar, a shade divided into sections and pivoted together at one end, an inwardly turned flange formed at the opposite end of said shade, said flange being secured to the annular offset of the collar and means for locking the said collar upon a lamp socket.

4. The combination with a lamp guard formed with a split collar and a locking means, of a shade made in sections pivoted together at one end and an inturned flange formed at the opposite end of said shade and secured to said collar.

In testimony whereof I affix my signature.

FREDERICK W. PENNOCK.

Copies of this patent may be obtained for five cents each, by addressing the "Commissioner of Patents, Washington, D. C."
